FOLDING BOOM FOR LINE TRUCKS

Norman F. Hurst, Aurora, Oreg., assignor to Ralph M. Osvold and Norman F. Hurst, a co-partnership doing business as Hurst Truck Utilities, Portland, Oreg.

Application April 28, 1953, Serial No. 351,648

5 Claims. (Cl. 212—8)

1

My invention relates to improvements in folding booms, and is particularly adapted to be used in connection with service line trucks having to do with electric transmission lines, telephone lines and the like.

The primary object of the invention is to mount a lifting boom on a line truck that can be automatically stored over the top of the truck while not in use.

Another object of my invention is to be able to operate the boom by a single hydraulic cylinder wherein the load being lifted by the boom is supported by a connecting rod connected to the piston rod of the hydraulic cylinder in such a manner that a tension is placed on the rod by the cylinder while the load is being lifted.

The object of using this method in supporting the boom under loads is that it is much safer and eliminates any danger of buckling the piston rod of the cylinder in the supporting of the load.

I have provided means associated with the cylinder and connecting rod, of locking the connecting rod to the boom while transferring the boom to its folded or storage position. In this case the piston rod performs a pushing action instead of a pulling action, the reason for this is that it requires very little movement of the rod to perform the folding action of the boom as well as the operating action.

These and other incidental objects will be apparent in the drawings, specification and claims.

Referring to the drawings:

Figure 1 is a side sectional view of the body of a line truck, together with a sectional view of my new and improved boom structure.

Figure 2 illustrates the boom in folded position.

Figure 3 is the rear view of Figure 1, partially broken away for convenience of illustration.

Figure 4 is an enlarged detail of the connection between the connecting rod and the piston rod, partially in section, taken on line 4—4 of the broken line position of the boom in Figure 1.

Figure 5 is an enlarged sectional view of the mounting of the boom to the truck, partially broken away for convenience of illustration.

Figure 6 is a plan sectional view, taken on line 6—6 of Figure 5.

Figure 7 is a sectional view, taken on line 7—7 of Figure 3, looking in the direction indicated.

Referring more specifically to the drawings:

The body of a conventional line truck is in-

2

dicated by numeral 1 and it consists of side walls 2, usually opened at the rear and having the front wall 3. The side walls are relatively thick due to the fact that shelving and compartments 5 are built within these walls for storing equipment.

I have found that my boom can best be mounted to the truck by way of the brackets 4. These brackets may consist of channel-like members secured to the rear ends of the sides 2 of the body as well as by the bosses 5 to the bottom 6 of the truck by any suitable means as bolts 7.

Bearing pins 8 and 8A are fixedly secured between the sides 9 of the brackets 4 and are adapted to support the boom 10 in the following manner: Forming part of the boom are jaws 11 and 12. While the boom is in storage position as illustrated in Figure 2, the jaws 11 engage the cross pin or bearing 8 and are locked thereon by the locking pin 13. When the boom is raised to the position shown in Figure 1, full lines, the jaw 12 engages the cross pin 8A. The locking bolt 13 is then removed from the jaws 11 and passed through the tips of the jaws 12 for holding these jaws to the pin 8A while the boom is in operating position.

A hydraulic cylinder 14 is pivotally mounted to the bracket 15 at 16. Its piston rod 17 is pivotally connected at 18 to a connecting rod 19. The upper end of the connecting rod is pivotally connected at 20 to the outer end of the boom 10, best illustrated in Figures 1 and 3. The lower end of the connecting rod is secured to the cross member 21 of the boom while the boom is pivotally connected to the upper pin 8 as shown in Figures 1, 2 and 3. The said connecting rod has jaws 22 for engaging the cross member 21, the said jaws being secured thereto by the locking bolt 23.

When the boom is in working position, the connecting rod 19 and the piston 14 operate as indicated by the broken lines in Figure 1. While the connecting rod and the piston rod are operating in this position they are locked in alignment by the locking bolt 24, referring to Figure 4 particularly. The connecting rod 19 has an elongated pocket 25 with a bottom 26 against which the piston rod 17 engages while being held in the position shown in Figure 4 by the locking bolt pin 24. This maintains the connecting rod and piston in alignment, although there would be other ways of accomplishing this same result.

The usual hoisting gear 27 is mounted in the

bottom of the truck with the lifting cable 28 running to the cable sheave 29, terminating in the usual hook 30. The hydraulic cylinder 14 could be located in the broken line position as indicated by numeral 31 in Figure 2.

I will now describe the operation of my new and improved folding boom for line trucks. When the boom is in folded position the connecting rod 19 is locked to the cross member 21 of the boom 19 by way of the jaws 22 and the locking bolt 23. When it is desired to raise the boom, hydraulic fluid is applied to the cylinder 14, which will push the said boom up, pivoting the same about the pin 8 to the position shown in Figures 1 and 3. This will bring the lower jaws 12 of the boom in registry with the lower pin 8A.

The locking bolt 13 is then transferred from the jaws 11 to the jaws 12, locking these said latter jaws to the pivot pin 8A. The locking bolt 23 is then removed from the jaws 22 of the connecting rod 19 so that the connecting rod will be released from the cross member 21. This will permit the connecting rod and piston to assume the broken line position as indicated in Figure 1. Then as the piston rod is pushed out, it will lower the boom as indicated by the broken line position, and it will be noted that this is a direct pull in the supporting of the end of the boom, which it is agreed by linemen is the proper method of supporting the boom with safety, therefore this is one of the outstanding objects of my new and improved boom. It will be noted that little piston travel is required to operate the same in either the folded position or in operating position.

When the boom is brought to the position shown in Figure 1, full lines, the cable 28 will support the load adjacent the rear of the truck, then all that is necessary to do is to position the same so that it can be pushed into the truck by the workman.

What is claimed is:

1. A folding boom hoisting apparatus comprising a support member, a boom member, releasable pivotal connections between said members at different elevations and including horizontal pivots on one of said members and open bearing elements on the other of said elements and respectively cooperative with said pivots, and a fluid operable jack pivotally connected between said members and including a cylinder pivotally mounted on said support member, a piston rod operable in said cylinder, a connecting rod pivotally connected between said boom member and said piston rod, and means cooperative between said connecting rod and respectively between said boom member and said piston rod for se-

lectively connecting said connecting rod rigidly with said boom member or said piston rod, whereby said connecting rod forms an extension of said piston rod when rigidly connected by said means with said piston rod and the pivotal connection between said piston rod and said connecting rod functions as a pivotal connection between said piston rod and said boom member when said connecting rod is rigidly connected by said means with said boom member.

5 2. An apparatus as defined in claim 1 wherein in said connecting rod is pivotally connected to said boom member adjacent the free end thereof and the distance between the pivotal connections of said connecting rod is shorter than the distance between its pivotal connection with said boom member and the nearest of said releasable pivotal connections.

10 3. An apparatus as defined in claim 2 wherein in said means includes releasable clamp means between said connecting and piston rods for releasably holding said rod in rigid relationship.

15 4. An apparatus as defined in claim 3 wherein in said means includes releasable clamp means between said boom member and said connecting rod for releasably holding said connecting rod in rigid relationship to said boom member.

20 5. A folding boom hoisting apparatus comprising a supporting structure having a pair of laterally spaced pivot elements aligned along a first horizontal axis, a boom member having two converging legs rigidly connected at their upper ends to each other and being provided intermediate their ends with auxiliary pivot means for permitting the boom to swing about a second horizontal axis spaced upwardly from said first horizontal axis, and a fluid operable jack pivotally connected between said legs and including a cylinder pivotally mounted on said supporting structure, a piston rod operable in said cylinder, a connecting rod pivotally connected between said boom member and said piston rod, and means cooperative between said connecting rod and said piston rod for selectively connecting said connecting rod rigidly with said piston rod, whereby said connecting rod forms an extension of said piston rod when rigidly connected by said means, and the auxiliary pivot means functions as a pivotal connection when 25 said boom member is being folded and unfolded.
